UNITED STATES PATENT OFFICE.

MAX KOPPE, OF NEW YORK, N. Y., ASSIGNOR OF ONE-HALF TO JOHN B. VERHOEVEN,
OF NEW YORK, N. Y.

NONSINKABLE CAR FLOAT AND CARGO BARGE.

Application filed November 1, 1923. Serial No. 672,064.

To all whom it may concern:

Be it known that I, MAX KOPPE, a subject of the King of Belgium, and a resident of the city, county, and State of New York, have invented certain new and useful Improvements in Nonsinkable Car Float and Cargo Barges, as set forth in the following specification.

My invention relates to non-sinkable car float and cargo barges designed with a series of watertight compartments running parallel with the length of the barge.

The object of my invention is to provide a series of watertight compartments in such a manner that should a collision result in the leakage or destruction of any one of the same, the barge would nevertheless float.

A further object of my invention is to enable either side of the barge to be elevated by displacing the opposite side by the introduction of water ballast, either by pumping same into the compartments or through the manhole openings placed in each compartment, into one or more of the series of watertight compartments, which is often a great advantage in enabling a barge to level up to the track levels on the land side, for the car float type.

A further object of my invention is to provide a barge of this type containing watertight compartments at each end thereof so that by inserting water ballast in some conventional manner in either of said compartments the other and opposite end of the barge may be caused to be elevated to meet slight discrepancies in the track levels on the shore end, for the car float type.

A further object of my invention is to provide a barge of such construction that it will be difficult to capsize the same with the resultant throwing of the cars into the water, by reason of the facility with which water ballast may be immediately placed in any conventional manner to offset any capsizing condition, for the car float type.

A further object of my invention is to provide barges of the type described, which will readily adapt themselves for purposes of repair without the necessity of drydocking, by reason of the fact that my construction makes it possible to insert water ballast in any conventional manner into one or more of the watertight compartments and thereby cause the opposite side or portion

or end of the barge to be elevated above the water level and thereby make possible any necessary repairs.

A further object of my invention is to provide cargo barges of such construction that only a portion of the cargo may be damaged in the event of collision, by reason of the cargo being located in the separate several watertight compartments easily accessible by removing the several hatch covers.

A further object of my invention is to provide a barge of simple and hence extremely economical construction, at the same time being of non-sinkable construction, and also greatly increase the structural strength of the barge by virtue of the double shell design throughout.

Referring to the accompanying drawings forming a part of this specification, in which similar letters indicate like parts in the several views, Fig. 1 is an elevation in perspective of the side of my invention, Fig. 2 is a plan view of same, Fig. 3 is a perspective view of a section of the barge, Fig. 4 is a cross-section elevation of a preferred embodiment of my cargo barge, and Fig. 5 is a plan view of the deck of the same.

As will be observed, I provide a series of watertight compartments running parallel with the length of the barge, designated as A on opposite sides of the boat. I also provide watertight compartments at both ends of the barge D and C. It will be observed that I also employ in a preferential embodiment of my invention bulkhead partitions across the barge designated X and Y, which automatically produce further watertight compartments B.

In order to provide access to my series of side compartments and also the end compartments of the car float barge, I have provided a series of manholes in same, designated in the drawing by G, through which water may be inserted manually or by pump, but it is to be understood that the insertion of water into these compartments in any manner is within the scope of my invention. In the cargo type I provide hatch covers E of wood or other suitable construction, and in a preferential embodiment I provide gangways F depressed below the general normal level of the deck, for the purpose of facilitating the removal and replacement of the cargo hatch covers E. It will be ob-

served that should any one of the watertight compartments become punctured below the water line, due to collision or otherwise, the construction is of such nature that the other compartments are quite ample to float the barge in normal operating position. It will also be observed that should any of the watertight compartments become punctured below the water line, due to collision or otherwise, only the cargo in that particular compartment could be damaged by water.

It will now be observed that any of the aforesaid objects of my invention relating to the ballasting of the barge for purposes of docking, repairing or eliminating capsizing may be readily accomplished by inserting water into the compartments A, B, C or D, through manholes G or otherwise.

Having thus described my invention, what I claim and desire to secure by United States Letters Patent is:

1. In a non-sinkable cargo barge a combination of a plurality of water tight compart-

ments forming the sides and ends of said barge, traverse bulkhead partitions forming water tight sub-compartments and sub-cargo compartments, hatchway covers over such watertight compartments, gangways extending parallel to the length of said barge and depressed below the level of the said hatchways as and for the purposes herein described.

2. In a non-sinkable cargo barge, a combination of a plurality of watertight compartments forming the sides and ends of said barge, traverse bulkhead partitions forming watertight sub-compartments and sub-cargo compartments, hatchway covers over such watertight compartments, gangways extending parallel with the length of said barge and depressed below the level of said compartments equipped with means for admitting water into the same, all as and for the purposes herein described.

In witness whereof I have hereunto signed my name this 17th day of October, 1923.

M. KOPPE.
